UNITED STATES PATENT OFFICE

ERNEST H. HOLZWORTH, OF BUFFALO, NEW YORK

BLAST-FURNACE TUYÈRE

Application filed July 11, 1927. Serial No. 204,696.

This invention relates to improvements in the tuyères used in connection with blast furnaces.

One of its objects is to provide a tuyère of this character which has been designed to reduce to a minimum the burning out of the tuyère at its nose and thereby materially reduce the maintenance costs of blast furnaces.

Another object of the invention is to provide a novel and effective method of continuously agitating and keeping in motion the molten materials in the furnace in the vicinity of the tuyère and preventing the same adhering to the tuyère and burning it.

15 In the accompanying drawings:—Figure 1 is a vertical longitudinal section of a tuyère embodying my invention, the same being mounted in the wall of a blast furnace. Figure 2 is a transverse section thereof on line 2—2, Fig. 1. Fig. 3 is a sectional view, similar to Fig. 1, showing a modified form of the invention.

Similar characters of reference indicate corresponding parts throughout the several views.

The numeral 10 indicates a part of the furnace wall in which the improved tuyère is mounted in the usual and well known manner. As is customary, the tuyère consists of a substantially frusto-conical body 11 made of a copper alloy or other appropriate material and having the usual passage 12 for the admission of a continuous blast of air to the furnace, this passage being connected at its 35 outer end with the source of air supply by a pipe 13. The tuyère-body has a cooling compartment 14 surrounding its air passage and through which water or other fluid is circulated by means of an inlet pipe 15 and an outlet pipe 16 connected to the outer end wall of said body, as shown in Fig. 1.

In practise, the molten metal and other materials in the furnace form and collect around the underside of the nose of the tuyère in substantially the manner shown in the drawings and burn the tuyère-nose in a comparatively short time, necessitating the renewal of the tuyère from time to time at a considerable cost. The present invention is 45 designed to agitate the molten materials gathered around the nose of the tuyère in such a manner that they will be kept away from the tuyère body and thus reduce to a minimum the possibility of burning the same. To this end I preferably introduce a portion of the 55 air blast flowing through the tuyère-passage 12 through a port or opening 17 formed at or a suitable distance behind the nose end of the tuyère-body and extending in a downwardly and forwardly inclined direction, as shown in Fig. 1. By this construction, a continuous blast of air of sufficient pressure is introduced through the port 17 to agitate the molten materials in the vicinity of the nose-end of the tuyère with the result that they are 60 constantly kept in motion. The introduction of this blast of air directly into the molten materials of the furnace and in substantially the direction indicated in the drawings distributes the eddy currents which normally 65 form at the nose of the tuyère due to the whirling motion of the main air blast introduced through the tuyère passage 12, thereby preventing the molten material from pocketing or gathering around the tuyère-body and 70 burning its nose.

If desired, the blast of air for agitating the molten materials may be introduced through a separate pipe 18, as shown in Fig. 3. This pipe is joined by a collar 19 to a pipe-section 80 20 arranged in the tuyère-body and reliably sealed in the rear end and bottom wall of the latter to prevent leakage of the cooling fluid from the compartment 14.

I claim as my invention:—

1. A blast furnace tuyère, comprising a body having a passage disposed adjacent to and under the nose end of the tuyère for delivering air under pressure into the molten materials of the furnace.

2. A blast furnace tuyère, comprising a body having a passage for the admission of air to the furnace above the level of the molten materials therein and an auxiliary passage disposed adjacent to and under the nose end of the tuyère for delivering air under pressure substantially downwardly into the molten materials of the furnace to keep them in constant motion about the nose end of the tuyère.

3. The method of preventing the burning

of a blast furnace tuyère, which consists in introducing a blast of air downwardly and forwardly through the tuyère and discharging it adjacent to and under the nose end 5 of the tuyère into the molten materials of the furnace for the purpose of agitating the molten materials adjacent thereto and keeping them in a state of motion.

ERNEST H. HOLZWORTH.
